UNITED STATES PATENT OFFICE

CURTIS S. CRAFTS, OF OAK PARK, ILLINOIS, ASSIGNOR TO GOSS PRINTING PRESS COMPANY, A CORPORATION OF ILLINOIS

SHEET CUTTING, COLLECTING, AND FOLDING MECHANISM

Application filed December 24, 1929. Serial No. 416,229.

The invention relates to new and useful improvements in sheet cutting, collecting and folding mechanisms and more especially to such improvements as applied to fast rotary printing presses.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, construction, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a fragmentary elevation, partly in section, of a mechanism embodying the invention, taken substantially on line 1—1 of Fig. 2;

Fig. 2 is a vertical section taken substantially on line 2—2 of Fig. 1;

Fig. 3 is a fragmentary side elevation, looking at the upper part of Fig. 1 from the left;

Fig. 4 is a transverse vertical section through the cutting, collecting and folding cylinder and the cooperating cutting cylinder, showing the opposite end from Fig. 1, and taken substantially on the line 4—4 of Fig. 5; and

Fig. 5 is a fragmentary top plan of the mechanism shown in Fig. 4, with associated parts.

The invention is directed to providing a novel sheet cutting and folding mechanism having optionally usable collecting means, which is simple and sturdy in construction, eliminates many parts which are necessary in the usual types of such mechanism, and which is easily changed from collecting to non-collecting operation and vice versa.

The invention further provides a mechanism of the kind described, wherein the sheets cut from a running web may be optionally collected upon the folding-off cylinder, which

likewise carries one of the cutting elements, the cutting being effected in such manner and location that the sheets are cut off and optionally collected in position for folding off, and the sheets follow the same simple and direct path when there is no collecting but instead direct folding-off of the product as cut off from the web received from the longitudinal formers or other mechanisms.

By means of this mechanism, the webs and sheets always follow a very short and direct path through the mechanism, and this path is not changed irrespective of whether or not there is collection of the sheets cut from the running web. The cross-association of webs may be simply effected directly from either side, due to the simplicity and the position of the mechanism.

There is further provided by my invention rotary, blade-equipped folding means, wherein a single blade may be utilized to effect the folding-off of either a collected or uncollected product through regulably controlling the number of actuations of the folding means in relation to the revolutions of the folding mechanism.

In realizing combinedly these and other objects there are provided a combined cutting, folding, and optionally operable collecting, cylinder, with a cutting, non-collecting cylinder coacting therewith to cut off sheets from a running web fed directly to the bite of the two cylinders, the alternative collecting or non-collecting being effected by regulation of the actuating means for the folding devices on the first-mentioned cylinder.

Means are likewise provided for varying the impaling pin, or equivalent sheet holding and releasing, action so that these likewise may be very simply, easily and quickly changed, either for collecting or non-collecting operation.

The invention in certain of its features provides an embodiment having the general characteristics stated, as well as others, wherein the folding mechanism is controlled and operated either for collecting or non-collecting by rotary actuating means, and preferably by a rotary cam having slots therein, and known

as the "Husby cam movement", although the invention in certain of its features is not thus limited.

It will be understood that the foregoing general description of the invention, and the following detailed description as well, are explanatory and exemplary of the invention, but are not restrictive thereof.

Referring now to the embodiment of the invention illustrated by way of example in the accompanying drawings, a running web supply is received from a suitable source, such as a fast rotary printing press, in which case the web supply is longitudinally folded, and usually associated. The web or webs are run over a former 1, having pairs of forming and forwarding rollers 2.

The sheet cutting, optionally collecting and folding-off means comprises a multi-way cylinder having an odd number of sheet supporting and collecting surfaces thereon (for cooperation with the usual arrangement of plates on the form cylinders of a printing press, that is, either two or four plates around), such sheet supporting spaces being usually three in number. The folding-off devices are located medianly of the respective sheet-supporting surfaces, and a cutting cylinder, cooperating with the multi-way cylinder to cut the sheets from the running web, is positioned preferably on the horizontal axial plane with the multi-way cylinder.

As embodied (Figs. 1, 2 and 4), the multi-way cylinder 10 is fixed on a shaft 12, which is journaled in the machine side frames 13 and 14. The cooperating cutting cylinder 18 is fixed on a shaft 19, journaled at 20 in the folder side frames 13 and 14. This cylinder is located substantially beside the collecting cylinder, and they preferably have their axes in the same horizontal plane. The web is preferably delivered directly to the sheet-cutting locus, which is likewise located preferably on the axis of the former from which the main web supply comes. Thus the web and sheets take a short and direct path and maximum space is afforded for cross-association when it is employed. Gear wheels 21 and 22, fixed respectively on the shafts 12 and 19, cause the two cylinders to rotate together. As shown, the cooperating cutting cylinder 18 has a circumference equal to the length of two sheets, and cuts twice for every revolution of the cylinder. Two male cutting members 26 and 27 are mounted diametrically opposite in the cylinder 18, and three female cutting members 28, 29 and 30 are mounted in cylinder 10, a sheet length apart circumferentially, and cooperate with the male cutters to cut the sheets from the running webs.

The embodied form of folding-off mechanism (Figs. 1, 2 and 4) comprises a rotary blade mechanism, to which is imparted a half rotation in passing the folding-off rollers 33 and 34 to fold off the sheets into the bite of the folding-off rollers. As embodied, each of

these rotary blade mechanisms comprises a shaft 37, mounted at its ends in bearings 38, formed in the ends of the cylinder 10. Each of these shafts is provided with two seats 39 and 40 for folding blades 41, but my invention contemplates the use of either one or two folding blades for each folding mechanism, as embodiments of optional means for collecting or non-collecting folding-off from cylinder 10.

In the embodied form of actuating and controlling means for the rotary blade folding-off mechanisms, when only a single blade is used for each of the folding-off devices, one end of each of the shafts 37 projects beyond the head of cylinder 10, and fixed on the projecting end of each of the respective shafts 37 is a cross-arm 47, carrying at either end thereof a pair of cam rollers 48 and 49. These cam rollers run on the inner face of a fixed circular cam track 53, mounted by means of supports 54 on the side frame 14 of the machine. The folding blade actuating device at the folding-off locus comprises the rotatable, slotted cam disc 55, having therein the cam slots 56, 57 and 58. The cam disc is integral with or fixed to a gear wheel 59, fixed to a stub shaft 60, journaled within a boss 61, fixed to and extending inwardly from the side frame 14. The gear wheel 59 meshes with a broad-faced gear wheel 63, fixed on the shaft 12 of cylinder 10, whereby the cam and cylinder are rotated in timed relation. During the folding operation, the foremost roller 48 as it comes to the lower gap in the cam ring 53, enters the corresponding slot 58 in the rotary cam, and shaft 37 is thereby given a semi-rotation due to the relative movement of the cylinder and cam, and the roller 49, which is then in the lead, again takes to and runs along, as the leader, on the cam ring 53 as the folding device leaves the cam slot. In this respect it is the usual operation of the Husby cam movement.

In accordance with one feature of the invention, control devices are provided for the folding device, selectively movable into different positions to cause collecting or non-collecting operation. When a single folding blade is used on each of the folding-off devices of the cylinder 10, means are provided for optionally imparting an additional semi-rotation to the folding-off device at an intermediate point, before it again approaches the locus of the folding-off rollers, thus causing the folding-off device to operate non-collecting and to fold off the sheets from the particular sheet supporting surface of the cylinder 10 at each passing of the folding-off rollers. Means are likewise provided for silencing this additional actuating means, to cause the single bladed folding device to collect before folding off. With this setting of the mechanism, each folding-off device receives a semi-rotation in passing the fold-

ing-off rollers, and thus when a single blade is used, although the folding-off device always cooperates with the rotary cam 55, there is a folding-off operation only every second time that the mechanism passes the folding-off rollers, and thus a collecting of two groups of sheets is effected, and they are folded off together. There is thus effected alternatively regulable rotary movement 10 of the folding devices to effect either collecting or non-collecting operation.

In the embodied form of said alternative control mechanism means are provided for selectively effecting rotary movement of the folding devices at one or more points in their rotary path. As embodied, a carriage or supporting slide 73 is mounted in guideways formed in a supporting bracket 74, fixed upon the machine side frame 14. Fixed to and downwardly projecting from the slidable support 73 is a bracket 75, the lower end of which is formed into an arcuate guide member 76 which, in one position of slide 73, constitutes a continuation of the circular track of the cam 53, across the median gap therein, whereby the respective folding blade actuating arms with their rollers will run continuously along the circular cam guide 53 and will be actuated only at the folding-off locus.

In the embodied means for imparting the extra semi-rotation to the folding-off devices, another bracket or supporting plate 81 is fixed to the slidable support 73, and extends downwardly therefrom. In the lower end of plate 81 is journaled a shaft 83, which is likewise journaled in a bushing 84 in the side frame 14 of the folder. Shaft 83 is both rotatable and longitudinally movable in said bushing bearing 84, but is shouldered so that it is rotatable in its support 81, but will move longitudinally therewith. Fixed on the inner end of shaft 83 is a gear wheel 85, to which is fixed a rotary slotted cam 86, which is the same in structure and operation as the cam 55 already described. The gear wheel 85 meshes with the broad-faced gear wheel 63 fixed on the shaft 12 of the folding cylinder 10, whereby the parts 40 rotate in timed relation, as gear 85 always remains in mesh with gear 63, as the cam bridge piece 76 or the rotary cam 86 are alternatively moved into alinement with the circular cam guide 53.

The embodied form and means of alternatively setting or moving the cam bridge piece 76 and the rotary cam device 86 into operative relation with the folding devices comprises a rod 91, fixed to the slidable support 73 and extending outwardly through an aperture in the side frame 14 of the folder. At its outer end rod 91 has a pin and slot connection 92 with an arm 93, fixed on a shaft 94, which is journaled in a bracket 95, fixed on the folder frame. A hand-actuable

lever arm 96 is fixed to the other end of the shaft 94, and is provided with a suitable locking device 97, whereby either the cam or the bridge piece may be moved to and be held in operative relation with the passing folding devices. The mechanism is thus settable for either collecting or non-collecting operation.

The means for effecting a collecting or non-collecting movement of the sheet holding and releasing devices of the collecting cylinder, as embodied, comprises a series of impaling pins 110, mounted in close proximity to the corresponding sheet-cutting device on the cylinder 10. The pins 110 are mounted on a series of arms 111, fixed on a shaft 112, journaled at its ends in the heads of the cylinder 10. One end of the shaft 112 projects outside the cylinder, and said exterior end has fixed thereon an arm 113 carrying a cam roller 114. These rollers run in a grooved cam track 115, formed in a cam disc 116, the hub 117 of which is journaled loosely on the shaft 12 of the cylinder 10.

A driving gear 123 is mounted on the hub 117 of the cam plate with a spline 124, whereby the gear wheel 123 may be moved axially on the hub 117 of the cam disc 116, but the cam disc and gear wheel rotate together. A clamping screw 125 may be provided for holding the gear wheel in desired position on the hub. Gear wheel 123, in one of its positions, meshes with a driving gear 129 fixed on the shaft 119 of the cutting cylinder 118. When the mechanism is so connected, the cam disc 116 has a three-to-two forward rotation relatively to the cylinder 10, and thereby the respective impaling pins will be actuated only every second time that they pass the folding-off position.

To effect consecutive actuation of the impaling pins for each rotation of the cylinder 10 cam disc 116 is held stationary. The gear wheel 123 is slipped from full line to broken line position in Fig. 5, and thus passes out of mesh with its driving gear 129, and passes into mesh with the teeth of a holding detent member 130, and thereby the cam plate 116 is held stationary, and the impaling pins are retracted on each rotation of the folding-off cylinder 10.

If desired alternative folding-off action may be effected by taking on and off a second folding blade for each of the folding devices. In such case, the cam track of the settable device will be kept in alinement with the guiding cam ring for the folding actuating devices. It is much speedier and simpler to use the settable device, as the mere shifting of the hand lever changes all the folding devices and the entire folder from collecting to non-collecting and vice versa.

The manner of operation of the foregoing described mechanism will be clearly under-

stood from the description, and need not be restated here.

The invention in its broader aspects is not limited to the specific mechanisms shown and described but departures may be made therefrom within the scope of the accompanying claims without departing from the principles of the invention and without sacrificing its chief advantages.

10. What I claim is:—

1. A sheet collecting and folding mechanism including in combination a multi-way collecting cylinder, a folding device mounted on said cylinder, folding-off rollers, and means for causing the folding device to coact with the folding-off rollers on every passing of the folding-off rollers or only on a plurality of said passings.

2. A sheet collecting and folding mechanism including in combination a multi-way collecting cylinder, a folding device having a folding blade mounted on said cylinder, folding-off rollers, and means for causing the folding device to coact with the folding-off rollers on every passing of the folding-off rollers or only on a plurality of said passings.

3. A sheet collecting and folding mechanism including in combination a multi-way collecting cylinder, a folding device on said cylinder, folding off rollers and means operable to cause the folding device to coact with the folding off rollers on every passing of the folding off rollers, and a portion of said means being optionally displaceable to cause the folding device to coact with the folding-off rollers only on a plurality of said passings.

4. A sheet collecting and folding mechanism including in combination a multi-way collecting cylinder, a folding device having a folding blade mounted on said cylinder, folding-off rollers, and a pair of means one of which is operable by an attendant to cause the folding blade to fold off on every passing of the folding-off rollers or only on a plurality of said passings.

5. A sheet collecting and folding mechanism including in combination a multi-way collecting cylinder, a rotary folding device mounted on said cylinder, folding-off rollers, and means for causing the folding device to coact with the folding-off rollers on every passing of the folding-off rollers, a portion of said means being optionally displaceable to cause the folding device to coact with the folding-off rollers only on a plurality of said passings.

6. A sheet collecting and folding mechanism including in combination a multi-way collecting cylinder, a rotary folding device having a folding blade mounted on said cylinder, folding-off rollers, and a pair of means one of which is optionally operable for causing the folding device to coact with the folding-off rollers on every passing of the fold-

ing-off rollers or only on a plurality of said passings.

7. A sheet collecting and folding mechanism including in combination a multi-way collecting cylinder, a folding device mounted on said cylinder, folding-off rollers, and means for causing the folding device to coact with the folding-off rollers on every passing of the folding-off rollers or only on a plurality of said passings, said means including a control mechanism for the folding device selectively movable into different positions to cause collecting or non-collecting operation.

8. A sheet collecting and folding mechanism including in combination a multi-way collecting cylinder, a rotary folding device having a folding blade mounted on said cylinder, folding-off rollers, and means for causing the folding device to coact with the folding-off rollers on every passing of the folding-off rollers or only on a plurality of said passings, said means including a control mechanism for the folding device selectively movable into different positions to cause collecting or non-collecting operation.

9. A sheet collecting and folding mechanism including in combination a multi-way collecting cylinder, a rotary folding device mounted on the collecting cylinder, folding-off rollers, and means for effecting alternatively regulable rotary movement of the folding device to effect collecting or non-collecting operation.

10. A sheet collecting and folding mechanism including in combination a multi-way collecting cylinder, a rotary folding device mounted on the collecting cylinder, folding-off rollers, and means for alternatively effecting rotary movement at one or more points in the path of the folding device to effect collecting or non-collecting operation.

11. A sheet collecting and folding mechanism including in combination a multi-way collecting cylinder, a rotary folding device mounted on the collecting cylinder, folding-off rollers, and a plurality of rotary means one of which is displaceable for effecting alternatively regulable rotary movement of the folding device to effect collecting or non-collecting operation.

12. A sheet collecting and folding mechanism including in combination a multi-way collecting cylinder, a rotary folding device mounted on the collecting cylinder, folding-off rollers, and rotary means for alternatively effecting rotary movement of each folding device at one or more points in the path of the folding device to effect collecting or non-collecting operation.

13. A sheet collecting and folding mechanism including in combination a multi-way collecting cylinder, a rotary folding device mounted on the collecting cylinder, folding-off rollers, and rotary means for imparting rotation to each of the folding devices on a

revolution of the multi-way cylinder, and other rotary means optionally operable to effect collecting or non-collecting operation.

14. A sheet collecting and folding mechanism including in combination a multi-way collecting cylinder, a rotary folding device mounted on the collecting cylinder, folding-off rollers, a plurality of devices for imparting rotary movement to the folding device at different points in its rotation, and means for selectively operating said devices to effect collecting or non-collecting action.

15. A sheet collecting and folding mechanism including in combination a multi-way collecting cylinder, a rotary folding device mounted on the collecting cylinder, folding-off rollers, a plurality of devices for selectively imparting either a semi-rotation or a full rotation to the folding device to effect collecting or non-collecting operation.

16. A sheet collecting and folding mechanism including in combination a multi-way collecting cylinder, a rotary folding device mounted on the collecting cylinder, folding-off rollers, a circular cam track controlling the movement of the folding device, an actuating device at the folding-off rollers for effecting rotary movement of the folding device in passing the folding-off rollers and a second actuating device at another point in the cam track alternatively settable to effect collecting or non-collecting operation.

17. A sheet collecting and folding mechanism including in combination a multi-way collecting cylinder, a rotary folding device mounted on the collecting cylinder, folding-off rollers, a circular cam track controlling the movement of the folding device, an actuating device at the folding-off rollers for effecting rotary movement of the folding device in passing the folding-off rollers and a second device having a section of the cam track and an actuating mechanism alternatively movable into coaction with the folding device to effect collecting or non-collecting operation.

18. A sheet cutting, collecting and folding mechanism including in combination a multi-way collecting cylinder, a cutting cylinder contacting and cooperating with said collecting cylinder to cut sheets from a web, a folding device mounted on said cylinder, folding-off rollers, and means for causing the folding device to coact with the folding-off rollers on every passing of the folding-off rollers or only on a plurality of said passings.

19. A sheet cutting, collecting and folding mechanism including in combination a multi-way collecting cylinder, a cutting cylinder contacting and cooperating with said collecting cylinder to cut sheets from a web, a rotary folding device having a folding blade mounted on said cylinder, folding-off rollers, and means for causing the folding device to coact with the folding-off rollers on

every passing of the folding-off rollers or only on a plurality of said passings.

20. A sheet cutting, collecting and folding mechanism including in combination a multi-way collecting cylinder, a cutting cylinder adjacent to and cooperating with said collecting cylinder to cut sheets from a web, a rotary folding device having a folding blade mounted on said cylinder, folding-off rollers, and means for causing the folding device to coact with the folding-off rollers on every passing of the folding-off rollers or only on a plurality of said passings, said means including a control mechanism for the folding device selectively movable into different positions to cause collecting or non-collecting operation.

21. A sheet cutting, collecting and folding mechanism including in combination a multi-way collecting cylinder, a rotary folding device mounted on the collecting cylinder, a cutting cylinder cooperating with said collecting cylinder to cut sheets from a web, folding-off rollers, and means for effecting alternatively regulable rotary movement of the folding device to effect collecting or non-collecting operation.

22. A sheet cutting, collecting and folding mechanism including in combination a multi-way collecting cylinder, a rotary folding device mounted on the collecting cylinder, a cutting cylinder cooperating with said collecting cylinder to cut sheets from a web, folding-off rollers, a plurality of devices for imparting rotary movement to the folding device at different points in its rotation, and means for selectively operating said devices to effect collecting or non-collecting action.

23. A sheet collecting and folding mechanism including in combination a multi-way collecting cylinder, sheet holding and releasing means on the collecting cylinder, and devices for causing said means to release the sheets on every revolution or on a plurality of revolutions of the collecting cylinder, a rotary folding device having a folding blade mounted on said cylinder, folding-off rollers, and means for causing the folding device to coact with the folding-off rollers on every passing of the folding-off rollers or only on a plurality of said passings, said means including a control mechanism for the folding device selectively movable into different positions to cause collecting or non-collecting operation.

24. A sheet collecting and folding mechanism including in combination a multi-way collecting cylinder, a rotary folding device mounted on the collecting cylinder, sheet holding and releasing means on the collecting cylinder, and devices for causing said means to release the sheets on every revolution or on a plurality of revolutions of the collecting cylinder, folding-off rollers, and means for effecting alternatively regulable

rotary movement of the folding device to effect collecting or non-collecting operation.

25. A sheet collecting and folding mechanism including in combination a cylinder having a plurality of sheet collecting spaces thereon, folding devices located medianly of the collecting spaces, sheet cutting devices at the ends of said collecting spaces, a cutting cylinder cooperating with said sheet cutting devices, folding-off rollers, and means for causing the folding devices alternatively to coact with the folding-off rollers on every passing of the folding-off rollers or on a plurality of said passings.

15 26. A sheet collecting and folding mechanism including in combination a cylinder having a plurality of sheet collecting spaces thereon, folding devices located medianly of the collecting spaces, sheet cutting devices at the ends of said collecting spaces, a cutting cylinder located substantially horizontally with respect to the collecting cylinder and cooperating with said sheet cutting devices, folding-off rollers, and means for 20 causing the folding devices alternatively to coact with the folding-off rollers on every 25 passing of the folding-off rollers or on a plurality of said passings.

27. In a sheet folding mechanism, a collecting cylinder, sheet holding and releasing means thereon, an endless cam track therefor, and means for optionally imparting rotational movement to said cam track to cause said sheet holding and releasing means to release the sheets on every revolution, or on 30 a plurality of revolutions of the collecting cylinder.

28. In combination, folding-off rollers, a sheet collecting cylinder having an uneven 40 number of sheet collecting surfaces thereon, a rotary folding device having two oppositely positioned folding blades, one blade at least being removable, and means for actuating the folding device every time it passes the folding-off rollers.

29. In combination, folding-off rollers, a sheet collecting cylinder having an uneven 50 number of sheet collecting surfaces thereon, a rotary folding device having two oppositely positioned folding blades, one blade at least being removable, means for actuating the folding device every time it passes the folding-off rollers, and means for actuating the folding device at an intermediate point 55 in the rotation of the collecting cylinder.

In testimony whereof, I have signed my name to this specification.

CURTIS S. CRAFTS.
